UNITED STATES PATENT OFFICE.

CHARLES E. MATTESON, OF ALLENTEWON, PENNSYLVANIA.

ROD-REEL.

SPECIFICATION forming part of Letters Patent No. 440,578, dated November 11, 1890.

Application filed August 15, 1889. Serial No. 320,822. (No model.)

To all whom it may concern:

Be it known that I, CHARLES E. MATTESON, a citizen of the United States, residing at Allentown, in the county of Lehigh, State of Pennsylvania, have invented certain new and useful Improvements in Rod-Reels, of which the following is a specification, reference being had therein to the accompanying drawings.

- 10 This invention relates to reels for use in connection with rod-mills; and the main object in view is to provide a means for receiving and coiling a rod as it emerges from the final rolls of a train, so that not only will a large floor space in the mill be freed for other purposes than the reception of such rod, but the rod itself will be put into a more convenient form for subsequent handling and treatment.
- 15 Other objects and advantages of the invention will appear in the following description, and the novel features thereof will be particularly pointed out in the claims.

Referring to the drawings, Figure 1 is a side elevation, with parts in vertical section, of a rod-drum and its appliances constructed in accordance with my invention; and Fig. 2 is a plan of the same.

Like letters of reference refer to like parts in both figures.

Let A A represent the final rolls of a train employed for the manufacture of rods from billets or other form of stock, and B the floor-plates usually employed in rolling-mills.

- 35 At a convenient distance from the rolls A is mounted a suitable standard or frame-work C, having a riser or other desired means D for the support of a guide-tube E, one end of which is in a sufficiently close proximity to the rolls A to receive therefrom the advancing or leading end of a rod as it passes therebetween. The opposite end of the guide-tube is curved so as to direct a rod passing therethrough downward. In this instance the tube E is made in two sections, the one being straight, projecting toward the rolls and adapted to slide telescopically within the other, which is connected with the support D, whereby the receiving end of the guide-tube 50 may be adjusted at different distances from the rolls.

The frame-work or standard C is aper-

tured, as at C', to form a bearing, in which is rotatably mounted a sleeve F, having a flange F', which bears upon the standard. The 55 sleeve may also have a flange F², adapted to bear upon the lower face of the standard, in which case, if the flanges be integral with the sleeve, as shown, the standard-bearing would consist of separable parts bolted together, as 60 is usual in constructing bearings for integrally-flanged journals.

To the lower flange of the sleeve is secured a delivery-tube or lay-off G, having the form of a compound curve with its delivery end 65 tapered transversely, and upon the upper portion of the sleeve is a rigidly-mounted belt or band pulley H; or any desired system of gearing may be employed. The bent section of the guide-tube E projects into the 70 sleeve F, and the interior bore of the latter is gradually reduced to coincide with that of the lay-off G at the point where the two join each other.

In the floor-plate B an opening B' is formed 75 of a size and shape to substantially agree with that of the drum I, and said opening leads into or communicates with a pit J, formed beneath the floor. Within the pit is arranged any suitable framing J' to support 80 the connected and operating parts of the drum. Mounted in any desired manner upon such framing are bearing-plates K⁴ K⁴, through which the spindle I' of the drum passes. The body of the drum terminates in 85 an upwardly and inwardly projecting annular flange I², which facilitates the removal of a coil of wire therefrom, and also permits the rotation of the extreme and delivering end of the lay-off closely to the periphery of 90 the drum without forming in the lay-off any abrupt bend, whereby the passage of the rod therethrough is not impeded, and, furthermore, the rod is up to its very end under the full control of the lay-off, and is neatly coiled 95 thereby. This latter advantage exists whether the flange I² be present or not. At K' a lever K is pivotally connected with the spindle-drum, said lever being fulcrumed in a bracket K², and pivotally attached at K³ to 100 rod L, carrying at its upper end a platform L', which is held substantially level with the floor-plate B by any suitable means. In this instance a latch is provided and adapted to

be operated by a hand-lever N, pivoted to and extending above the floor, so as to come into contact with and hold the platform L' and rod L in the position shown in Fig. 1, 5 and so as to detach the latch from the rod and permit it and the rod to rise by reason of the weight of the drum and its spindle acting on the end K' of the lever K.

The operation is as follows: A suitable band 10 or belt H' being driven from any desired source of power, the lay-off G is rotated, and its delivery end travels a path close to the periphery of the drum. The rod X emerges from the rolls A A, enters and travels along 15 the guide-tube E until the leading end strikes the curved portion, by which it is deflected into the rotating sleeve, and is guided by its coned interior into the non-abruptly-curved lay-off. As the rod reaches the floor-plate it 20 is by the rotation of the lay-off rapidly whipped around the drum, and when leaving the roller is drawn more or less snugly thereagainst, and the successive coils are laid upon each other until the following end of the rod 25 passes out of the lay-off, and is whipped thereby against the drum. The latch M is now released from the rod L, and the drum falls within the pit, the edges of the opening B' of the floor-plate retaining the coil and 30 serving to strip the same from the drum. The coil may now be transported bodily away for further treatment. The operator now depresses by a foot or standing upon the platform, so as to bring the drum into position to 35 receive another coil.

By the apparatus thus described the equally long distance of floor-space required to receive an uncoiled rod from the rolls is rendered useful for other purposes, and the 40 rod is put into a convenient form.

What I claim as new is—

1. In a wire-reel, a rotary lay-off having

the form of a compound curve and having its delivery end curved backwardly and downwardly in the line of its intended rotation, 45 whereby it is adapted to terminate below the upper edge of the drum, substantially as specified.

2. In a wire-reel, a rotary lay-off having the form of a compound curve with its delivery 50 end curved backwardly and downwardly in the line of its intended rotation and tapered transversely, substantially as and for the purpose specified.

3. A vertical reciprocative pitted drum, a 55 system of levers for reciprocating said drum, and a locking mechanism for retaining the drum in a desired position, substantially as described.

4. The combination, with the floor-plates 60 and the final rolls of a train, of the rod-guide, a rotary lay-off, a drum vertically reciprocative through an opening in said floor-plates, and a platform operatively connected with the drum, substantially as described. 65

5. The combination, with a standard having a bearing, of an annular flanged sleeve provided with a single rod-passage and a pulley, and a curved lay-off secured to the sleeve to constantly register with the rod-passage of 70 the sleeve, substantially as described.

6. The combination, with a rotary lay-off, of a reciprocative drum and an open-sided case, whereby a coil, when formed, may be withdrawn from the reeling apparatus without lifting the same from the floor, substantially as described. 75

In testimony whereof I affix my signature in presence of two witnesses.

CHARLES E. MATTESON.
